D. Murless.

United States Patent Office.

D. MURLLESS, OF HOLYOKE, MASSACHUSETTS.

Letters Patent No. 96,467, dated November 2, 1869.

IMPROVED LATHE-BATH AND SPONGE-HOLDER FOR DENTISTS' USE.

The Schedule referred to in these Letters Patent and making part of the same.

To all whom it may concern:

Be it known that I, D. MURLLESS, of Holyoke, in the county of Hampden, and Commonwealth of Massachusetts, have invented a new and improved Lathe-Bath and Sponge-Holder for Dentists' Use; and I do hereby declare that the following is a full, clear, and exact description thereof, reference being had to the accompanying drawings, making a part of this specification, and to the letters of reference marked thereon, in which—

Figure 1 is a plan view of said invention;

Figure 2 is a vertical sectional view, the plane of section being indicated by the line $z z$ in fig. 1; and

Figure 3 is a transverse sectional view, the plane of vertical section being indicated by the line $y y$ in fig. 1.

In the practice of dentistry, small revolving wheels, of corundum or like hard substance, are constantly in use for cutting and shaping artificial teeth, and for general grinding-purposes, and the high speed at which such wheels are driven, (generally by a foot-treadle,) and the hardness of the substances ground upon them, make frequent wetting necessary, both to wash the wheels from the porcelain grit and to keep them cool.

To provide a receptacle for the water, and to furnish means for thoroughly and constantly wetting such wheel, when revolving, is the object of my invention.

The construction of said device is as follows:

A small trough, A, preferably of cast-metal, is supported at the proper height above the work-bench by means of the upright rod C passing through an opening in the ear a^1 , which is cast upon the trough, and the set-screw e.

To allow some movement of the support C upon the work-bench, it is set in the slotted base B, which is held fast to the bench by a thumb-screw, so that the whole device can be swung round out of the way, if necessary.

As it is desirable to be able to apply the water to either side of the wheel, and either at the front or the rear face, I provide four sponge-holders, H, H, H¹, and H², each of which is furnished with a round stem, E.

The side holders H H are made alike, being simply curved plates for binding the small strips of sponge I upon.

The holder H¹ is made T-shaped, while H² is curved in the direction of its length, and may be turned at right angles to the position shown in fig. 1, so as to cover a considerable arc upon the periphery of the corundum wheel.

As some grinding is done upon the sides of the wheel as well as upon the face, the side sponge-holders H H may also be turned at a greater or less angle to the positions shown in fig. 1, as also may the holder H¹. In fine, the arrangement of the four sponge-hold-

ers is such that any number of them may be put into contact with the wheel at once, while the rest are thrust out of the way; and further, those in contact can be turned into the position which will wash the wheel most effectually.

To sustain the stems E E of the sponge-holders, ears $a a a a$ are cast, at four points, upon the trough, in the upper surface of each of which is a dovetailed recess, into which a metallic cap, D, slides, its sides being bevelled to fit the dovetailed recess.

A round hole is made in each ear and its cap, (see fig. 2,) in which the stem E slides, and is also revolved, if necessary.

To bind the stem and cap in place, when properly set, a set-screw, s, is applied to each, as shown in the drawings, one of the set-screws, s¹, being placed in the cap D for convenience of access, while the other three are tapped into the ears a from the under side.

It is evident, that by turning the set-screw, the stem will be prevented from moving, while the edges of the cap will be forced up against the bevelled sides of the dovetailed recess, and firmly held.

It will also be obvious, that the means of adjustment are so numerous that the operator can find no difficulty in adapting the device to any work he may have in hand, without rising from his work-bench, and that all throwing of the water by the centrifugal force of the corundum wheel, and all necessity for using one hand to wet the wheel, are entirely avoided.

I am aware that the caps D D may be cast as a part of the ears $a a$, and with less expense, but I prefer to employ the loose cap, to allow a more perfect adjustment of the sponge-holders.

For the support of the end sponges, I have, in some cases, substituted, for the end holders H¹ H², hereinbefore described, simple wires, stretched across the ends of the trough from side to side, and for some purposes of dentists' practice, I believe this change to be advantageous.

Having described my invention,

What I claim as new therein, and desire to secure by Letters Patent, is—

The water-trough A, supported so as to be adjustable beneath the corundum wheel, and having ears $a a$, in combination with the sponge-holders H H H¹ H², stems E, and set-screws s, the whole constructed and arranged substantially as set forth.

In witness whereof, I have hereunto set my hand, this 1st day of February, A. D. 1869.

D. MURLLESS.
